UNITED STATES PATENT OFFICE.

WILLIAM J. CARTER, JR., OF AKRON, OHIO.

STRETCHING FRAME FOR SHEET MATERIAL.

Application filed June 28, 1927. Serial No. 202,079.

This invention relates to frames for holding household curtains, quilts or the like in stretched condition.

In such frames heretofore commonly employed adjustment of the frame for articles of different sizes has required the removal of bolts from apertures formed in the frame members or the resetting of C-clamps, and so far as I am aware such frames have not comprised means for assuring the proper right-angle relation of adjacent frame members to each other. Another defect of frames heretofore commonly used is that the overlapping of adjacent frame members at the corners has resulted in the work-retaining hooks or pins on adjacent frame members being so positioned as to hold their respective portions of the work in different planes, which has prevented the work from being held in true plane form, or from being anchored to both of the overlapped frame members, in the region closely adjacent the corner of the frame.

My chief objects are to avoid these several objections, to provide a frame adapted for ready assembly and adjustment and disassembly, to provide a self-squaring frame, to provide for the anchoring of the work in substantially the same plane throughout the corner portions thereof, to provide for strength and durability of the structure, to provide for rigidity of the frame in service, and to provide more detailed advantages which will be manifest.

Fig. 1 is an elevation of a curtain stretcher frame embodying my invention in its preferred form.

Fig. 2 is a section on line 2—2 of Fig. 1.

Fig. 3 is a section on line 3—3 of Fig. 2.

Fig. 4 is a perspective view of one of the corner clamping members.

Referring to the drawings, the preferred embodiment of the invention here shown comprises a pair of opposite frame members or bars 10, 10, each of which may comprise two sections, 10^a and 10^b, secured together in extension of each other by means of a channel member 11 of sheet metal fitting upon the two frame sections and permanently secured to one of them, as by the rivet 12, and detachably secured to the other by means of a bolt 13 and wing-nut 14, the section 10^a being

adapted to be used as a complete frame member, without the section 10^b, for curtains or other articles of narrow width.

Each of the frame members 10 is formed with a clamp-receiving body portion 15 (Fig. 2) and a toe portion 16 extending from the base thereof and provided near its outer edge with a row of work-anchoring pins 17, 17, 60 so inclined with relation to the plane of the frame that a piece of sheet material mounted on the frame under tension will remain at the bases of the pins, against the toe portion of the frame member.

The other two frame members or bars, 18, 18, disposed opposite each other in the frame, are each preferably formed with outer faces 19, 19 perpendicular to the plane of the frame and with clamp-engaging faces 20, 20 parallel with the plane of the frame, and may be rectangular in cross-section, as shown. Each of these frame members is provided with a row of work-anchoring pins 21, 21 adapted to permit a corner clamp to be slid along and in contact with the clamp-engaging face 20 of the frame member without interference with the pins, and for this purpose each pin preferably is pivoted at its base on a nail 22 driven into the outer face of the frame member, 70 so that the pin can be turned about the nail to a position in which it lies entirely on the outer face 19 of the frame member, entirely out of the plane of the member's clamp-engaging face 20, and alternatively may be turned to a position such that it projects past the said clamp-engaging face 20, in position to have the work mounted thereon. The pins 21 are preferably of springy metal and so formed as to bear strongly against the outer face 19 of the frame member in a portion remote from their pivots, and the said face of the frame member is preferably formed with a groove 23 for each pin, adapted to receive the pin to hold it in operative position.

Each of the pins 21 is preferably formed with an elbow 23^a at a position in substantially the same plane as the work-engaging bases of the pins 17 of the frame members 10, so that the work will assume upon the pins 21 a position such that it will be held in the same plane throughout its extent and consequently may be anchored upon the pins 21 as well as upon the pins 17 throughout the length of its

5 margins, without distortion of corner portions of the work out of its general plane. I do not wholly limit my claims, however, to pins 23 having elbows adapted to hold the work away from the frame member 18, as the cross-sectional form of the frame member 10 results in the work-anchoring bases of the pins 12 being close to the plane of the adjacent face of the frame member 18.

10 For adjustably securing the frame members 10 to the frame members 18 at the corners of the frame, in overlapped relation, I provide at each corner of the frame a clamp member 24 having a frame-squaring face 25 adapted to receive and clamp against the outer face of the adjacent frame member 10 and, at right angles to the face 25 but so offset therefrom as to provide for the overlapping of the frame member 10 upon the frame member 18, a frame-squaring face 26 adapted to receive and clamp against the inner face of the adjacent frame member 18. The corner clamp member 24 is formed with a flange having a plane face 27 adapted to receive the adjacent frame member 10 and with a flange having a plane face 28 adapted to receive the adjacent frame member 18, the faces 27, 28 being disposed at right angles to each other, along the frame-squaring faces 25, 26, but in the same plane with each other, so as to support the frame members 10 and 18 substantially in contact with each other in overlapped relation.

15 For clamping the frame member 10 to the frame-squaring face 25 a bolt 29 provided with a wing-nut 30 at the outer side of the clamp member 24 is mounted in an aperture in the member 24 and is formed at its inner end with a laterally disposed hook portion 29^a adapted to take over the body portion 15 of the frame member 10, the bolt 29 being adapted, upon loosening of the nut 30, to be turned upon its own axis to turn the hook portion 29^a away from, and thus to release, the frame member 10.

20 Similarly a bolt 31 provided with a wing-nut and having a hook portion 31^a is mounted in the corner clamping member 24 and adapted to engage the frame member 18 to hold it against the frame-squaring face 26 and readily to release the frame member 18 upon being turned to swing its hook portion 31^a away from the frame member.

25 For mounting the frame in upright position, each of the frame members 18 is mounted in a channel iron 32 backed against a horizontal foot member 33 and secured thereto by a bolt 34 extending through the foot member 33, the channel iron 32 and the frame member 18 and provided with a wing-nut 35 and the channel iron 32 is formed with a stamped and bent ear 36 fitting against the upper face of the foot member 33 and secured in position thereon by a screw 37, the structure being

30 such as to provide a strong and rigid right-

angle connection of the frame member 18 with the foot member 33.

35 In the operation of the device the work is anchored by its margins upon the pins 17 and 21 and the frame is expanded by sliding the frame members 10 and 18 in the corner clamping structures, the pins 21 adjacent the corner clamping members being turned down so as not to interfere therewith, and the bolts 29 and 31 are then tightened to hold the work 75 in stretched condition.

40 The tightening of the bolts 29 and 31 at the first corner automatically squares the adjacent frame members against the faces 25, 26 of the clamp member.

45 In disassembling the frame the frame members readily may be disconnected from each other by loosening and turning the bolts 29 or 31, and the frame members 18 readily may be disconnected from the foot members 33 85 by removing the frame members 18 from the bolts 34 and channel irons 32.

50 For work of narrow width the sections 10^b of the frame members 10 readily may be eliminated by removing the bolts 13, removing the sections 10^b from the adjacent corner clamping members and mounting the sections 10^a therein.

55 The pivoting of the pins 21 upon their nails 22 permits those within the work-engaging 95 reach of the frame member 18 to be turned to work-engaging position while those beyond the said reach are turned onto the face 19 of the frame member so as not to interfere with the sliding of the corner anchoring member 100 24 on the frame member.

60 The structure provides for convenient adjustment of the frame throughout a wide range of sizes in conjunction with the advantages that have been brought out in the description and in the above statement of objects.

65 Modifications are possible within the scope of the invention as defined in the appended claims.

70 I claim:

75 1. A stretching frame comprising two frame bars crossed substantially in contact with each other at a corner of the frame, a corner clamp comprising a unitary, rigid member formed with bar-contacting faces holding the bars in fixed angular relation and hook-bolts mounted in the said member and hooked over the bars to hold the latter respectively against the said faces, one of the bars being formed on its inwardly-facing side with a toe portion, work-anchoring pins mounted on the said toe portion, and work-anchoring pins pivoted on the outer face of the other bar, on axes transverse thereto and parallel with the plane of the frame, the pivotal axis of each of the last said pins being closer to the work-facing side of the bar than the length of the pin.

80 2. A stretching frame comprising two 130

frame bars crossed substantially in contact with each other at a corner of the frame, a corner clamp comprising a unitary, rigid member formed with bar-contacting faces holding the bars in fixed angular relation and hook-bolts mounted in the said member, hooked over the bars and holding the latter respectively against the said faces.

3. A stretching frame comprising two frame bars crossed substantially in contact with each other at a corner of the frame, a corner clamp comprising a unitary, rigid member formed with bar-contacting faces holding the bars in fixed angular relation and means on the said member clamping the bars respectively against the said faces, the said means comprising independently operable clamping members individual to the respective bars.

20 4. A stretching frame comprising two frame bars crossed in close proximity to each other at a corner of the frame, a corner clamp holding the bars in crossed relation, and a set of pins pivotally mounted on the outer 25 face of one of the bars on axes transverse thereto and parallel with the plane of the frame, the distance from the pivotal axis of each of the pins to the nearest face of the adjacent bar being less than the length of the 30 pin.

5. A stretching frame as defined in claim

4 in which each pin at a distance from its pivot bears against the face of the bar on which it is pivoted and is held in different positions of adjustment by its own resilience. 35

6. A stretching frame comprising two frame bars crossed at a corner of the frame, a corner clamp comprising a unitary, rigid member formed with bar-contacting faces holding the bars crossed in fixed angular 40 relation, flanges on said member for positioning the bars respectively on said faces, and hook bolts mounted on said member and turnable to take over the respective bars and alternatively to positions such as to permit the 45 bars to be removed from the said member without being slid lengthwise therefrom.

7. A frame clamp comprising a unitary, rigid member formed with two angularly disposed faces for holding respective frame bars in fixed angular relation to each other and with bar-positioning portions which with the said faces define two bar-receiving spaces, the said portions having bar-contacting surfaces lying in a single plane parallel to the 55 plane of the frame and said surface lying on opposite sides of said plane, and means on the said member for clamping respective frame bars against the said faces.

In witness whereof I have hereunto set my 60 hand this 24th day of June, 1927.

WILLIAM J. CARTER, JR.
